UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

NAILING MACHINE.

Application filed January 5, 1927. Serial No. 159,118.

My invention relates to machines for driving nails, it being more particularly directed to the jack-post or work-support of that type of apparatus disclosed in Letters Patent of the United States No. 1,269,654, Standish, June 18, 1918. This form of jack-post is arranged for use in attaching heels to shoes by means of nails driven from the inside, it being hollow and containing a reciprocating driver-plunger, the drivers of which are forced up through nail-tubes in the jack-top. To adapt the apparatus to operate properly upon different sizes of shoes, the tubes are made adjustable in slots in the jack-top. These slots are necessarily so long that, for certain adjustments of the tubes, as for very large shoe-sizes, openings are left through which nails are likely to fall. Since the jack-post is cast with a practically unbroken side wall for the sake of strength, and as the plunger carrying the drivers is guided by its sliding fit in a bore through the frame-bracket upon which the jack rests, these nails accumulate within the jack-body, and, gathering about the plunger, tend to wedge and thus score and rapidly wear it, so it must be replaced at a substantial expense. This invention has for its object the provision of a structure by the use of which this difficulty is avoided. This combines with the jack-post and plunger, already outlined, a bushing furnishing a guide for the plunger and constructed and arranged to permit the discharge of nails from the interior of the jack-post. The form of the bushing is such that it provides nail-passages, these being preferably between arms which radiate from an annular portion in which the plunger is guided.

The bushing is shown as mounted by the extension of the outer extremities of its arms over the jack-post support, and the upper surfaces of these arms and the guiding annulus may be inclined so that the nails delivered to the openings between the arms will have little tendency to bridge the spaces and thus accumulate.

A particular embodiment of the invention is illustrated in the accompanying drawing, Fig. 1 being a vertical section through a jack-post and a portion of the supporting frame arranged in accordance with said invention;

Fig. 2, a broken top plan view of the jack;

Fig. 3, a vertical section on the line III—
III of Fig. 2; while

Fig. 4 shows the bushing of this invention in perspective.

At 10 appears a bracket projecting from the front of the frame of a nailing machine such as is disclosed in the patent previously mentioned. In the horizontal portion of this bracket is an opening 12, through which reciprocates a spindle or plunger 14 having at its upper end a head 16 carrying nail-drivers 18. The drivers operate in tubes 20, which extend vertically through slots 22 in the top plate 24 of a hollow jack-post 25, the side walls of which are spaced from the plunger. This jack-post is bolted in place upon the upper surface of the bracket about the opening 12. Heads 26 formed upon the upper extremities of the tubes rest upon the plate to support said tubes, which may be adjusted along their slots by a screw 28. This enables the operator to simultaneously draw the tubes in toward one another when heels are to be attached to shoes of small sizes, or move them out for the heel-ing of larger shoes. The drivers are correspondingly movable upon the plunger-head to permit this. At the extremes of adjustment of the driver-tubes, the openings through the jack-top may be of considerable size, amply large to allow the nails used in the heel-ing operation to fall through them into the interior of the jack-body.

To guide the plunger in its reciprocation, there is associated with the opening 12 a bushing, which has a main annular portion 30, the opening of which furnishes a sliding fit for the plunger. The external diameter of the annulus is as small as may be, having consideration for the provision of a wall of ample thickness as a guide for the plunger, thus leaving a space between it and the wall of the opening 12 of considerable width. Radiating from the annulus 30 are arms 32, here shown as three in number, which, at their outer extremities 34, overhang the upper face of the bracket, being seated in a depression 36 therein. The bushing may be held against upward displacement by screws 38 threaded vertically into the under sides of the arms, and with portions of their heads projecting beneath the lower wall of the bracket. Since the nails might bridge across the space between

the annulus and the arms, this tendency is minimized by inclining these. The upper edge of the annulus diverges downwardly from the plunger at 40, while the upper 5 faces of the arms bear surfaces 42 which diverge in the same direction from each other.

It will be seen that by my improved construction a guide of ample strength is furnished for the driver-plunger, and one which may readily be renewed if desired. With the plunger thus guided, nails falling 10 into the jack-post will either be at once discharged therefrom by direct travel through the passages between the arms, or, striking 15 upon the upper edges of either the annulus or arms, will be deflected by the inclined walls into the passages. In either case, the nails passing through the bushing will fall 20 entirely clear of the machine.

Having described my invention, what I claim as new and desire to secure by Letters Patent of the United States is:

1. In a nailing machine, a hollow jack-post 25 surrounding a bottom opening and having openings at its top, a reciprocatory plunger extending through the bottom opening and provided with drivers co-operating with the 30 openings at the jack-top, and a bushing furnishing a guide for the plunger and constructed and arranged to permit the discharge of nails from the interior of the jack-post.

2. In a nailing machine, a support 35 provided with an opening, a hollow jack-post rising from the support about the opening and having slots at its top, nail-tubes movable in the slots, a reciprocatory plunger extending through the support-opening into 40 the jack-post and spaced from the walls of said jack-post, drivers carried by the

plunger and operating in the tube-openings, and a bushing furnishing a guide for the plunger at the support-opening and having passages arranged to permit the discharge of 45 nails from the interior of the jack-post.

3. In a nailing machine, a support provided with an opening, a hollow jack-post rising from the support about the opening and having slots at its top, nail-tubes movable in the slots, a reciprocatory plunger extending through the support-opening into the jack-post and spaced from the walls of said jack-post, drivers carried by the plunger and operating in the tube-openings, and a bushing comprising an annular portion 50 furnishing a bearing for the plunger and arms radiating from the separated points about the annulus and secured to the support, the spaces between the arms being sufficient to permit the passage of nails therethrough.

4. In a nailing machine, a support provided with an opening, a hollow jack-post rising from the support about the opening and having slots at its top, nail-tubes movable in the slots, a reciprocatory plunger extending through the support-opening into the jack-post and spaced from the walls of said jack-post, drivers carried by the plunger 55 and operating in the tube-openings, a bushing comprising an annular portion furnishing a bearing for the plunger and arms radiating from the annulus and overhanging the support at their outer extremities, the upper surfaces of the annulus and arms being inclined, and securing means carried by the arms at their under sides and engaging the support.

In testimony whereof I have signed my 60 name to this specification.

THOMAS LUND.
